[57] CLAIM

The ornamental design for telephone set, as shown and described.

DESCRIPTION

FIG. 1 is a left side elevational view of a telephone set showing my new design, the side opposite being a mirror image thereof;

FIGS. 2 and 3 are respectively top and bottom plan views of the set in mated assembly;

FIGS. 4 and 5 are respectively front and rear elevational views thereof;

FIG. 6 is a bracket associated top plan view of the telephone stand unit, and a bottom plan view of the handset unit inverted and spaced apart from the stand; and

FIG. 7 is a right side elevational view of the handset unit shown alone for clarity of illustration, the side opposite being a mirror image thereof.

Fig. 1.

Fig. 2.

Fig. 3.

FIG. 4.

FIG. 5.

FIG. 6.

FIG. 7.
